1,990,540

THERMOSTATIC FURNACE REGULATOR

George W. Folk, South Bend, Ind.

Application January 30, 1932, Serial No. 589,953

5 Claims. (Cl. 236—15)

The invention relates to thermostatic furnace regulators of the type illustrated in my copending application, Serial No. 552,966, filed July 24, 1931, which have connection with and control the check and draft dampers of a furnace responsive to heat changes therein to provide a uniform furnace heat.

The object of the invention is to provide a device of this character having a pair of members formed of materials having different coefficients of expansion, and simple means connected with and actuated by relative expansion and contraction of said members to operate the dampers of a furnace.

15 A further object is to provide a device of this character having a pair of members formed of materials having different coefficients of expansion, and a damper-operating member pivotally carried by one member of said pair and having an eccentric pivotal connection with the other member of said pair.

20 A further object is to provide a device of this character having damper-operating means and an electric switch controlled by said damper-operating means.

25 With the above and other objects in view, the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

25 Figure 1 is a longitudinal vertical sectional view of the device.

Figure 2 is a longitudinal horizontal sectional view of the device.

40 Figure 3 is a longitudinal vertical sectional view of a modified construction of the device.

Figure 4 is a transverse vertical sectional view of the modified device taken on line 4—4 of Figure 3.

45 Figure 5 is a fragmentary longitudinal horizontal sectional view of another modified construction of the device.

Figure 6 is an enlarged fragmentary longitudinal vertical sectional view of the preferred embodiment of the device illustrating an electric switch operatively carried thereby.

50 Referring to the drawing, the numeral 10 designates a frame, preferably of U-section, which is adapted to be mounted in the head of a hot air furnace. A casing 11 is formed at one end of and preferably integrally with the frame 10, and

5 has an opening 12 therein communicating with the inner side of frame 10. One end of the casing 11 is open and mounts a cover plate 13. The casing 11 carries flanges 14 by which it may be secured to the head of a furnace, as indicated in dotted lines in Figure 1.

A transversely extending plate 15 is formed at the end of frame 10 opposite the casing 11 and is provided with an opening through which the end of a metal rod 16 extends. Nuts 17 are threaded 10 on rod 16 on opposite sides of plate 15 to secure the end of the rod 16 and frame 10 against relative movement. One or more transverse plates 18 similar to plate 15 are integrally formed with frame 10 in spaced relation and between the 15 casing 11 and plate 15. Suitable aligned openings are formed in these plates 18 for the reception of rod 16 which is slideable therein and guided thereby. The free end of rod 16 preferably terminates in spaced relation to casing 11 and fixedly 20 carries an aligned fitting 19 which projects into the opening 12 of casing 11.

A shaft 20 is rotatably journaled in the sides of the casing 11 substantially centrally thereof and mounts a disc 21. The disc 21 is positioned 25 adjacent one side of the casing and disaligned from the rod 16 and fitting 19, and carries a laterally projecting stud 22 in closely spaced relation to shaft 20. A link 23 is pivotally mounted on stud 22 at one of its ends and pivotally connected to fitting 19 at its opposite end, and is provided with a goose neck 24 at its stud connected end which permits it to overlay to shaft 20 without interference therefrom when stud 22 is positioned as shown in Figure 1. The periphery of 30 the disc is provided with a groove 25 for the reception of a damper-operating chain 26 which is fixedly held by pin 27 to prevent movement of the chain relative to the disc. The chain 26 passes from the casing 11 through suitable openings 28 and is connected to the furnace dampers. 35

Assuming that the coefficient of expansion of the rod 16 is greater than that of the frame 10, the device as illustrated in Figure 1 is being subjected to a high heat which has caused expansion 40 of rod 16 relative to frame 10. Upon lessening of the degree of heat to which the device is subjected the rod 16 will contract and pull upon the link 23, thereby rotating the disc 21 clockwise to pull upon one end of the damper-operating chain 26 45 and slacken the other end of the chain. Likewise, when greater heat is applied to the device the expansion of rod 16 pushes upon link 23 to rotate disc 21 in counter clockwise direction. It will be seen that this interconnection of the two 50

55 and 55

relatively expansible members by means of the disc mounting the chain forms a very simple and direct control for the furnace dampers.

A slightly modified construction of the device is illustrated in Figure 3, in which the substantially U-shaped frame 10 carries casing 11 having an opening 12 communicating with the inner side of the frame 10. The casing rotatably mounts a disc 21 over which chain 26 extends, and carries a stud 22 eccentrically thereof. A transversely extending plate 15 is carried by the opposite end of frame 10 and has fixedly secured thereto the end of rod 30 which is mounted in the frame 10 and extends through opening 12 into casing 11 where it is pivotally secured to stud 22. A goose neck 31 is formed on the stud-connected end of rod 30 to overlay the shaft 20 of the disc. Spaced transversely extending plates 32 are carried by the frame 10 and are provided with vertically elongated slots 33 through which the rod 30 passes. The construction of this modified type of device differs from that of the preferred type only in the unitary construction of the relatively expansible rod 30 which is connected at its opposite ends to plate 15 and stud 22, eliminating the pivotally interconnected fitting 19 and link 23 of the preferred construction, and in providing elongated guide slots in transverse plates 32. The operation of the preferred and this modified type of device is similar. As shown in dotted lines in Figure 3, the rotation of the disc induced by expansion and contraction of rod 30 causes the rod to raise and lower about its fixed connection with plate 15 as a pivot. This raising and lowering of the rod is accommodated by the slots 33 which guide the expansive and contractive movement of the rod relative to frame 10.

A further modified construction of the device is illustrated in Figure 5 in which the difference of the construction resides in the casing 11 and its contained chain controlling mechanism. In this construction a shaft 35 is journaled in the sides of the casing 11 and mounts a bevel gear 36 carrying a suitable stud eccentrically thereof which is pivotally connected with a link 37 pivotally carried at its other end by the relatively expansible rod 38. The gear 36 meshes with a bevel pinion gear 39 mounted on a shaft 40 journaled in the cover 41 of the casing 11. The shaft 40 also mounts a disc 42 over which the furnace damper controlling chain extends. By this construction it will be seen that a double increase in the amount of movement of the chain for a relatively slight movement of the rod 38 is obtained, which makes the device respond much quicker to slight changes in furnace temperature and consequently increases the effectiveness of the device.

In Figure 6 is illustrated an electrical switch cooperating with the preferred form of my device illustrated in Figure 1. In this construction a bracket 45 is pivoted to the casing 11 at 46 in spaced relation to the periphery of disc 21. The bracket 45 mounts a mercury arc switch 47 of conventional construction having lead wires 48. One end of bracket 45 carries a spring 49 secured at its opposite end to the casing, and which normally tilts the bracket to hold the switch in open-circuit position. An arm 50 extends from bracket 45 in spaced parallel relation to one face of disc 21 from which projects a stud 51 which is adapted to engage the arm 50 to tilt the switch to circuit-closing position. The cooperating switch and disc are arranged in a manner where-

by the switch will be positioned in open-circuit position upon expansion of rod 16 at high temperatures and will be moved to closed-circuit position against the action of spring 49 upon contraction of rod 16 at relatively low temperatures. This arrangement of the switch and disc permits of combined control of the furnace dampers as previously described and also permits simultaneous and cooperating control of a stoker operating motor, not shown; whereby, when the furnace temperature is low, the draft damper is opened and the stoker motor is started to feed fuel to the furnace, and when the furnace temperature raises to a predetermined point, the draft damper is closed and the stoker motor is stopped.

The invention having been set forth, what is claimed as new and useful is:

1. In a thermostatic furnace control, a pair of thermally expansive members having different coefficients of expansion fixedly secured together at one of their ends, an arcuate member pivotally carried by one of said thermal members adjacent the free end thereof, interconnecting means pivoted to the free end of the other thermal member and to said arcuate member eccentrically of its pivotal connection with the first thermal member, and furnace damper controlling means carried by said arcuate member to be actuated thereby.

2. In a thermostatic furnace control, a frame, a rod disposed in said frame and fixedly secured thereto at one of its ends, said frame and rod having different coefficients of expansion, a disc rotatably carried by said frame, means pivotally connecting the free end of the rod eccentrically of said disc, a flexible chain mounted on the periphery of said disc, and means carried by said disc and engaging said chain to prevent slipping of the chain on the disc.

3. In a thermostatic furnace control, a frame, a rod disposed in said frame and fixedly secured thereto at one of its ends, said frame and rod having different coefficients of expansion, a disc rotatably carried by said frame, a link pivotally connected to the free end of said rod adjacent said disc, said link being pivotally connected to said disc eccentrically thereof and a flexible member frictionally engaging the periphery of said disc for actuation thereby.

4. In a thermostatic furnace control, a frame, a rod disposed in said frame and fixedly secured thereto at one of its ends, said frame and rod having different coefficients of expansion, a disc rotatably carried by said frame, a link pivotally connected to the free end of said rod adjacent said disc, said link being pivotally connected to said disc eccentrically thereof, and furnace damper controlling means operatively connected to said disc.

5. In a thermostatic furnace control, a frame, a rod disposed in said frame and fixedly secured thereto at one of its ends, said frame and rod having different coefficients of expansion, a disc rotatably carried by said frame, a link pivoted to the free end of said rod and eccentrically of said disc, the disc-connected end of said link being curved to permit substantial alignment of the pivot of said link with the axis of said rod, and furnace damper control means fixed to the periphery of said disc.

GEORGE W. FOLK.
